UNITED STATES PATENT OFFICE.

WILLIAM A. LORENZ, OF HARTFORD, CONNECTICUT.

JAR OR TUMBLER CLOSURE.

1,322,913.

Specification of Letters Patent. Patented Nov. 25, 1919.

Application filed March 29, 1918. Serial No. 225,416.

To all whom it may concern:

Be it known that I, WILLIAM A. LORENZ, a citizen of the United States, residing at Hartford, in the county of Hartford and State of Connecticut, have invented a new and useful Improvement in Jar or Tumbler Closures, of which the following is a specification.

This invention relates to the construction of closures for food containing jars and tumblers which are held sealed by atmospheric pressure.

The object of the invention is to so form such closures that they may be cheaply made of thin metal, readily sealed by apparatus commonly used for this purpose, easily opened whether applied to jars or tumblers when it is desired to remove the contents, and will protect the edges of tumblers from breakage if dropped or roughly handled.

In attaining this end the center of the cap is made conical or dome-shaped in order that it may be stamped from thin sheet metal and have sufficient strength to prevent it from collapsing under atmospheric pressure after air has been exhausted from the inside of the receptacle and the sealing is effected. A curved inwardly opening annular groove is formed near the edge of the cap for receiving the packing gasket which spreads over the upper edge of the jar or tumbler when sealed, and the edge of the flange around the cap is flared or bell-shaped so that below the packing gasket it stands away from the wall of the jar or tumbler and provides a shoulder which is serviceable when it is desired to pry a sealed cap from a jar or force a sealed cap from a tumbler, and which also acts as a protecting means around the upper edge of a tumbler.

Figure 1 of the accompanying drawings shows a section of a food containing jar and its cap in unsealed relation. Fig. 2 is a similar view showing the jar and cap in sealed relation. Fig. 3 shows on larger scale a section of the edge of the jar and cap in sealed relation. Fig. 4 shows a section of a tumbler containing food and having its cap laid on in unsealed position. Fig. 5 is a similar view showing the cap sealed on the tumbler. Fig. 6 is an enlarged view of

a small section of the tumbler and cap in sealed relation. Fig. 7 shows a capped tumbler upset. Fig. 8 is a detailed view showing a method of removing a cap from a jar.

The cap 1 which is stamped from thin sheet metal is circular in outline and its center 2 is convexed—conical or dome-shaped so that while the metal is thin it cannot collapse under atmospheric pressure when sealed upon a receptacle. Around the cap near the edge is an inwardly opening annular groove 3 and outside of this groove is the flange which is flared outwardly or is bell-shaped so that its edge 4 will stand away from the wall of the receptacle, whether it be a jar 5 or a tumbler 6.

In the annular groove in the inside of the cap a flexible packing gasket 7 is placed. This gasket is shaped in a common way so that when the cap is first laid over the receptacle preferably but a small area of the gasket will rest upon the outer corner of the upper edge of the receptacle, as shown in Figs. 1 and 4. This permits air to be readily withdrawn from the interior of the receptacle by the commonly employed exhausting apparatus. After air has been sufficiently withdrawn from the interior of the receptacle and the closure is pressed down the gasket spreads itself over the upper edge and on the inside and outside of the mouth of the receptacle a sufficient distance to insure an efficient hermetic closure, as indicated in Figs. 2 and 5.

With a cap of this construction if the receptacle is in the form of a jar with a shoulder 8 on the outside below the rim, a knife blade or other implement 9 may be inserted between the outstanding edge of the cap and the shoulder on the jar and sufficient leverage obtained to render breaking the seal of the jar easy, as shown in Fig. 8. Or if the receptacle is a tumbler the outstanding edge of the cap is so far beyond the wall of the tumbler that a shoulder is provided which may be firmly seated on a table or other object and the tumbler drawn away from the cap so as to break the seal. Furthermore, the more or less flexible projecting edge of the cap forms a cushion which protects the edge of the tumbler if it

is dropped or should be knocked over, as shown in Fig. 7, or when two tumblers are bumped together.

The invention claimed is:

- 5 A food containing package hermetically sealed by atmospheric pressure, comprising the combination of a jar or tumbler and a thin metallic cap having an inwardly opening annular groove near its edge with a
10 flexible packing gasket located in said groove

and fitting upon the rim of the receptacle, said cap flaring outward beyond the gasket and terminating in a continuous annular thin edge that is greater in diameter than any other part of the cap and stands away 15 from the wall of the receptacle and forms a yielding protecting hood for the rim of the receptacle upon which the cap is held.

WILLIAM A. LORENZ.
